WEAVING LOOM

Kurt Schwabe, Bielitz-Bielsko, Poland

Application March 8, 1935, Serial No. 9,961
In Germany March 3, 1934

2 Claims. (Cl. 139—241)

The object of the present invention relates to a weaving loom provided with multiple shuttle change on both sides of the lay as well as automatic replacement or exchange of bobbins or shuttles for one or more colours, wherein the shuttle change can be effected at will and quite independently of the exchanging device, in contradistinction to similar weaving looms of this type already known, viz. to so called blending or mixing change-over automatic looms, which however only permit of a dependent and limited change of shuttles or a very limited exchange or replacement of bobbins. By means of the present invention the very wide field of weaving which was formerly reserved purely for the ordinary weaving loom, such as the weaving of millinery and Jacquard fabrics, is now available for automatic looms.

The basic idea of the invention is this, that, if the bobbin has run out, and if the bobbin or shuttle change is one sided, the shuttle with the empty bobbin is shot from the feeler side into an auxiliary shuttle box provided outside the shuttle box on the exchange side; the bobbins or the shuttle being exchanged for another suitable one, whereupon the shuttle with the full bobbin is again pushed into that compartment of the shuttle box, into which it would have been placed, if no bobbin or shuttle change had taken place.

For this purpose, if the bobbin or shuttle exchange has started, the picker is withdrawn out of the reach of the path of the shuttle on the change side, in order that the shuttle can freely enter into the shuttle box on the exchange side. The appended drawings show a constructional form of the present invention by way of example, and in these drawings.—

Fig. 1 shows a plan of the whole arrangement of the automatic exchanging device, and—

Fig. 2 shows a side elevation thereof;

Fig. 3 shows a plan view of the actuating rail on a larger scale, whereas—

Figs. 4 and 5 show the gearing for the bobbin exchange in elevation and side view, and—

Figs. 6 and 7 show a plan view of details of the gear.

Fig. 8 represents a travel-time diagram for the necessary motions for the bobbin exchange.

In the case of the embodiment shown on the drawings, the feeler mechanism is on the left side of the loom, which feels the bobbin in the manner known per se, between shuttle change and shuttle pick. The usual reserve bobbin magazine and the transerrer 23 are also shown. If the bobbin is empty, then the low tension elec-

tric current circuit is closed, thus energizing the automatic switch 1 which sets the motor 2 in motion. The switch 1 and the motor 2 are mounted on the driving gear box 3 into which the shaft of the motor 2 and the gear wheel 4 keyed thereunto reaches. When the motor is running it drives by means of the gear wheel 4 the gear wheel 5 which is rigidly connected to the gear wheel 6 both these two gear wheels running loose on the shaft or spindle 7. The gear wheel 9 keyed on the shaft 8 meshes with the gear wheel 6. The shaft 8 is rotatably mounted in the gear box 3. The eccentrics 10, 11, 12, 13 and 14 keyed on to the said shaft 8 rotate in unison with the said shaft 8. The eccentric 10 actuates the roller lever 15 the eccentric 11 the roller lever 16, the eccentric 13 the roller lever 17 all the said roller levers being rotatably mounted on the shaft or spindle 7. The eccentric 12 actuates the roller lever 18 mounted and keyed on the short spindle 20 and thereby also the lever 19 mounted on the same spindle, the said spindle 20 being rotatably mounted in the gear box 3.

The eccentric 14 acts by means of the lever 2 on the magnetic automatic switch 1.

A pull rope or rod 22 connects the lever 16 with the hammer or transerrer 23, a pull rope or rod 24 connects the lever 15 to the double armed lever 25, which is rotatably mounted on the shaft 26. The latter is mounted and seated in two arms 27a and 27b which are fixed to the sides of the gear box 3. A further pull rope or rod 28 connects the lever 25 to a bell crank lever 29 which is rotatably mounted on the trunnion 30, and embraces the picker spindle 31, the latter passing through a slot provided in the former. The trunnion 30 is located in the driver rail 32. The lever 10 is articulated by means of the rod 33 to the lever 34 and actuates the vertical uncoupling shaft 35 of the loom. A pull rod or rope 36 connects the roller lever 17 with a double lever 37 which resembles on one side the lever 25 but is on the other side provided with a flat surface 38, against which the shoe of the repeating apparatus 40 which is suitably bent or curved, rests. The repeating apparatus shoe 40 carries the striker 41 which penetrates into the exchanging or auxiliary shuttle box 42 and is enclosed by a sliding block 43 which is guided by the walls of the exchange box 42. The pin 39 is mounted on a Cardan joint 44 the bearing pins 45a and 45b are mounted on the arm 27b. The face 38 of the double lever 37 and the corresponding point of the two armed lever 25 are arranged in such a manner, that they are on a centre line with the

lay foot pin 46. The Cardan joint 44 is provided for the purpose to enable the repeater 41 to rock together with the lay.

The picker spindle 31 is rotatably mounted at one of its extremities on the trunnion or pin 47 on the driver rail 32, whereas the other extremity carries the slide member 48 which reaches around the picker 49 and is guided in a guide 50 and is displaceable therein. Fig. 8 shows the travels of the individual eccentrics and their relative positions. A complete revolution of the eccentric shaft 8 is sub-divided into 20 equal parts, designated with the numerals 1-19. The rest position at which the loom normally works is designated with 0.

The operation of exchanging a bobbin is the following viz: When the bobbin is empty, the electromagnetic switch 1 switches the motor 2 in, and the eccentric shaft 8 is caused to rotate thereby by means of the gear wheel pairs 4, 5 and 6, 9. The eccentrics 10, 11, 12, 13, 14 actuate according to their eccentric shape the corresponding roller levers, at an earlier or later moment. By reason of this arrangement the picker spindle 31 is, during the time the shuttle travels from the feeler to the exchange side, moved by means of the eccentric 10 from the position 1 into the position 2, and the loom is uncoupled or stopped by the eccentric 12 in such a manner that it comes to rest when the lay is at its rearmost position. The arriving shuttle thus flies over beyond the shuttle box 51 and into the change or auxiliary shuttle box 42, where it is caught up by the repeater 41 by means of the spring 52 (compare Fig. 4). At this point the bobbin is exchanged by reason that the eccentric 11 draws the hammer or transerrer 23 down. After the bobbin exchange has been effected the repeater 41 comes into action, it being actuated by the eccentric 13, and conveys the shuttle with the new bobbin into that compartment of the shuttle box, which it had just passed through. The curve of the eccentric 10 is of such a shape, that the picker was held during the whole of the time in the position 2. After the shuttle has entered the shuttle box the protruding portion of the curve of the eccentric 10 recedes and the picker returns into the position 1. The same holds good for the eccentric 12 which almost simultaneously throws the loom into action, which latter continues to work normally.

At this point the switch is thrown off by the eccentric 14 and the motor 2 is stopped. Consequently the shaft 8 comes to rest as do also the eccentrics 10, 11, 12, 13 and 14. The design of the pairs of gear wheels 4, 5 and 6, 9 is such that the hammer 23 only exchanges the bobbin at the moment when the shuttle has safely reached the shuttle exchange box 42.

It is of course self-evident that the exchange of the bobbin or of the shuttle can be effected in the

manner above described, without stopping the loom, if the width of the weave is correspondingly narrow. It is also not absolutely necessary to provide a motor, as the eccentrics 10, 11, 12, 13 and 14 could be mounted on any one shaft rotated during the bobbin change.

I claim:—

1. In an automatic weft replenishing weaving loom including a shuttle, shuttle box, a picker movable to and from picking position, a clutch controlled drive means, a reserve bobbin magazine at one side of the loom, a transerrer for supplying bobbins to the shuttle, and feeler means for indicating when a shuttle requires a filled bobbin; the combination of an auxiliary shuttle box disposed beyond said first shuttle box along the lay and beneath said magazine, and feeler operated means connected to said picker for moving it out of shuttle operating position when the weft is substantially exhausted whereby the shuttle will be propelled into said auxiliary shuttle box, and subsequently actuated feeler operated means operable to successively actuate said drive means clutch to stop the loom, move said bobbin transerrer to place a filled bobbin in said shuttle box, then return said shuttle to said shuttle box, then return the picker to shuttle picking position, and finally actuate said clutch to cause the loom to resume operation.

2. In an automatic weft replenishing loom including a shuttle, shuttle box, a picker movable to and from shuttle picking position, a clutch and drive means for the loom controlled thereby, a reserve bobbin magazine for the shuttle at one side of the loom, a transerrer for supplying bobbins to said shuttle, an auxiliary shuttle box disposed beyond said first shuttle box along the lay and beneath said magazine for receiving the shuttle that is to receive a filled bobbin from the magazine, means for returning a filled shuttle to the shuttle box from said auxiliary shuttle box, and feeler means for indicating when a shuttle requires a filled bobbin; the combination of a control unit arranged at the side of said loom below said auxiliary shuttle box, said unit comprising a frame, a motor carried by said frame, a cam shaft operatively connected to said motor and driven thereby, a cutout switch for said motor, separate cams on said shaft, different ones of said cams operatively connected to said drive means control clutch, picker transerrer, shuttle return means, and switch, respectively, said cams being arranged to actuate in the order set forth the said elements they control, the picker control cam being formed to maintain the picker out of shuttle picking position until the shuttle return cam has operated to return the shuttle to the shuttle box, and means for starting said motor.
